UNITED STATES PATENT OFFICE.

HARRY PATTEN, OF CHORLTON-CUM-HARDY, ENGLAND.

FOOT SUPPORT.

1,408,712.

Specification of Letters Patent.

Patented Mar. 7, 1922.

Application filed September 10, 1920. Serial No. 409,339.

To all whom it may concern:

Be it known that I, HARRY PATTEN, a British subject, residing at Station Bridge, Chorlton-cum-Hardy, county of Lancaster, 5 England, have invented certain new and useful Improvements in Foot Supports, of which the following is a specification.

The invention relates to improvements in foot supports designed to cause the wearer 10 to tread truly in the centre of the sole and to correct any tendency of the wearer to tread over to one side of the boot or shoe.

It consists of a loose support shaped along 15 one side approximately to the contour of the side of the boot or the side of the foot of the wearer and straight or approximately straight along the other side, and inclined from the inner to the outer side, the shaped side being of sufficient thickness to raise the 20 side of the foot the desired distance and the straight side as thin as possible not to form a ridge under the foot.

The invention will be fully described with 25 reference to the accompanying drawings.

Fig. 1 is a perspective view of the fitting.

Fig. 2 is a plan of same.

Fig. 3 is a section on line α — α Fig. 1.

The support A is shaped along the side α to approximately the contour of the side of the boot or the side of the foot of the wearer, and the other side α' is straight or approximately straight. The side α is formed of sufficient thickness to raise the side of the foot the desired amount, and 35 the side α' is made as thin as possible so

as not to form a ridge under the foot. The support A is thus wedge shape in cross section, as shown in Fig. 3, tapering from the side α to the side α' .

The support A is also tapered longitudinally at the ends b b' so that there will be no ridge where these ends meet the boot or shoe. The support may be held in position by pins passing through it into the boot or shoe, indicating marks c being shown on the 45 attachment for the pins.

The attachment may be made of cork, leather, rubber, wood, felt, vulcanized fibre, or other suitable material, and may be cut, ground, moulded or otherwise formed to the 50 desired shape.

What I claim as my invention and desire to protect by Letters Patent is:—

A foot support comprising a narrow strip extending the length of the boot or shoe 55 shaped along the outer side approximately to the contour of the boot or shoe and straight along the inner side which lies substantially along the longitudinal center of the shoe and inclined from the inner to the 60 outer edge to raise the edge of the foot of the wearer.

In testimony whereof I have hereunto set my hand in presence of two subscribing witnesses.

HARRY PATTEN.
